DESIGN FOR A CHAIR

Thomas B. Bond, Detroit, Mich., assignor to U. S.
Steel Furniture Manufacturing Corp., New
York, N. Y., a corporation of New York

Application April 3, 1945, Serial No. 118,844

Term of patent 3½ years

(CL. D15—1)

To all whom it may concern:

Be it known that I, Thomas B. Bond, a citizen of the United States and a resident of Detroit, in the county of Wayne and State of Michigan, have invented the new, original, and ornamental Design for a Chair, of which the following is a specification, reference being had to the accompanying drawing, forming part thereof, in which—

Fig. 1 is a side elevational view of a chair embodying my new design;

Fig. 2 is a front elevational view;
Fig. 3 is a top plan view;
Fig. 4 is a sectional view taken on the line 4—4 of Fig. 3;
Fig. 5 is a sectional view taken on the line 5—5 of Fig. 3;
Fig. 6 is a sectional view taken on the line 6—6 of Fig. 3.

I claim:

The ornamental design for a chair, as shown.
THOMAS B. BOND.
